UNITED STATES PATENT OFFICE.

DAVID G. SIMPSON, OF BROOKLYN, NEW YORK, ASSIGNOR TO LOOSE WILES BISCUIT COMPANY, OF LONG ISLAND CITY, NEW YORK, A CORPORATION OF NEW YORK.

DIE ROLLER.

Application filed May 26, 1922. Serial No. 563,813.

To all whom it may concern:

Be it known that I, DAVID G. SIMPSON, a citizen of the United States, and a resident of Brooklyn, in the county of Kings and 5 State of New York, have invented an Improvement in Die Rollers, of which the following description, in connection with the accompanying drawings, is a specification, like characters on the drawings representing 10 like parts.

This invention relates to die rollers and particularly to die rollers for material of dough-like consistency.

In order that the principle of the invention may be readily understood, I have disclosed a single embodiment thereof in the accompanying drawings, wherein—

Fig. 1 is a side elevation, with parts broken away and in vertical section, of a die roller 20 embodying my invention;

Figs. 2 and 3 are vertical transverse sections upon the lines 2—2 and 3—3 respectively of Fig. 1;

Fig. 4 is a plan view of one of the die 25 blocks; and

Fig. 5 is a vertical longitudinal section taken through the die roller.

A die roller, such as herein disclosed, may be used for many purposes, but is of particular 30 utility when used upon material of dough-like consistency, and especially upon food products material.

Heretofore so far as I am aware, it has been customary to provide a die roller with 35 a plurality of die blocks, but the blocks have been assembled in such manner as to render it very difficult to remove a defective block, and especially without disassembling or taking down the entire roller 40 and its several parts.

The die roller of my invention is so constructed that any defective die block can readily be gotten at and removed, a substitute block be positioned in place thereof 45 and the parts of the roller re-assembled in proper position with a minimum expenditure of effort and time.

Without limiting myself to that embodiment of the invention herein shown, I will 50 describe the preferred embodiment of my invention.

I provide a shaft 1 desirably having a key extending substantially the length of the roller and also desirably having a key 55 to hold fast upon the shaft a gear or driv-

ing member, such as 2. I provide two heads 3, 4, both of which have openings 5, 5 for the reception of bolts 6 extending substantially the entire length of the roller and receiving nuts 7.

I provide a series of die block rings 8. Any suitable number of such rings may be employed. Herein I have represented eight rings each at its surface being of the full width of a die block, one of said die 65 blocks being represented at 9 in Fig. 4.

Each of said die block rings is of polygonal shape, each being herein shown as having twelve faces, though obviously within the scope and purpose of my invention, any suitable number of faces may be provided. Each die block is provided upon its face with a suitable die formation 10, preferably embossed thereon, and which forms no part of my present invention and 70 may be varied as desired. A suitable number of screw holes are provided in each face of each die block ring as indicated in Figs. 2 and 3, four screw holes being preferably provided so that screws 11 may be received therein and enter screw holes 12 extending part way through only from the under faces of the several die blocks 9 at both sides of the radial supporting web. In this manner the several die blocks are 75 held securely in position, each upon a separate face of the die block ring to which it pertains. As shown, the die blocks of a single ring abut at their ends and the die blocks of adjoining rings abut at their sides. 80 While my invention is not limited in this respect, this is a desirable construction, as it tends to compactness and provides for a maximum number of die blocks.

The several rings are held fixedly in position by the bolts 6. If it be desired to remove a defective die block, this is accomplished by removing the nuts 7 at one of the heads 3 or 4, sliding said head along the shaft 1 and also sliding the necessary 85 number of die block rings along the shaft 1 until the ring having the defective die block is reached. This allows space for access to the inside of the die block ring having the defective die block so that the 90 screws 11 therefor may be removed, the defective die block taken out and another substituted therefor.

As shown, each ring 8 has a web 13 extending from its polygonal face inward 110

toward its hub or centre 14. This web may be of sufficiently less thickness than the polygonal faces of the ring to provide space for the screw holes and for the manipulation of the screws 11, the said web 13 being therefore preferably central with respect to the several polygonal faces thereof.

Obviously the die roller constructed in accordance with my invention may be used 10 in any suitable manner. According to one manner of use the roller is positioned at the bottom of a hopper containing dough, the dough being drawn by the die roller between itself and a contacting roller, and in the 15 continued rotation of the die roller the cakes or other products are separated from the die roller in any suitable manner not constituting a part of this invention and which therefore need not be described, inasmuch 20 as such means are well known in the art.

The die roller of my invention is particularly useful in connection with a dough of such rich consistency that it would fall apart if handled. Obviously the dough 25 product may be wafer, either filled or unfilled, or any other suitable product.

I have stated that each die block ring may have any suitable number of faces. Within the scope of my invention, the ring 30 may be circular and receive the die blocks thereon, each block having its inner face curved to correspond to the circular or like formation of the die block ring. I have employed the term "polygonal" throughout the 35 specification as including a circle.

Having thus described one illustrative embodiment of my invention, I desire it to be understood that although specific terms are employed, they are used in a generic 40 and descriptive sense and not for purposes of limitation, the scope of the invention being set forth in the following claims.

Claims—

1. A die roller comprising in combination, 45 a shaft, a pair of heads keyed thereon, a plurality of die block rings positioned in a laterally adjoining relation between said heads, bolts passing through said heads and rings to confine the parts in assembled position, each ring having a polygonal surface, and a series of die blocks detachably secured to the polygonal faces of each of said rings.

2. A die roller comprising in combination, 50 a shaft 1 having a driving gear 2, a pair of heads 3, 4 keyed upon said shaft and adapted to be slid therealong for assembling or disassembling the parts of the roller, a series of die block rings 8 likewise keyed upon said shaft 1, each ring having a radial web 55 13 and polygonal faces constituting the periphery thereof and a series of die blocks 9 secured by screws 11 inserted from the inside of the said polygonal faces, and bolts 6 for securing the said parts of the die 60 roller in position.

3. A die roller comprising in combination a shaft having driving means, a pair of heads keyed upon said shaft, a series of die block rings positioned between said heads, means extending through said heads and 70 rings for securing the parts in assembled position, each of said rings having a radially extending web, and relatively broad guide block receiving faces, and embossed die blocks detachably secured to the several 75 faces of said roller, the several die blocks of a single ring contacting at their ends and the die blocks of adjoining rings being in lateral contact.

4. A die roller comprising, in combination, 80 a shaft, a pair of heads thereon, a plurality of die block rings individually surrounding said shaft between said heads and held in position thereby, each of said rings having a hub keyed on said shaft, a relatively narrow radial web portion extending from said hub and a relatively broad circumferential surface to receive a plurality of die blocks, die blocks detachably secured in a series to the surface of said ring and 85 means extending longitudinally of the shaft and connecting said heads together and thereby securing the rings in position.

5. A die roller comprising in combination, 90 a shaft, a pair of heads thereon, a plurality of die block rings between said heads and held in position thereby, each of said rings having a continuous surface adapted to receive a plurality of die blocks in a ring like 95 formation, die blocks detachably secured to 100 said surface and constituting a ring like structure when in position and bolts securing said heads together.

6. A die roller particularly adapted for 105 use in cutting dough or like material comprising in combination, a shaft, a series of adjoining die block rings 8 upon said shaft, each ring having a hub 14 keyed to the shaft, a radial web portion 13 projecting 110 from said hub and a circumferential die block receiving flange at the outer end of said web, said webs being each substantially central relative to their respective flanges, a ring-like series of die blocks 9 on each of 115 said flanges, means 11 projecting through said flanges at opposite sides of their respective webs for removably securing the die blocks in position, and means for securing said die block rings against displacement longitudinally of the shaft but readily 120 releasable to permit their removal.

7. A die roller particularly adapted for 125 use in cutting dough or like material comprising in combination, a shaft, a series of adjoining die block rings 8 upon said shaft, each ring having a hub 14 keyed to the shaft, a radial web portion 13 projecting from said hub and having a plurality of transverse openings, a circumferential series of die blocks 130 removably supported at

the outer extremity of each of said flanges, the opposite ends of said bolts whereby the
a pair of heads 3, 4 keyed on said shaft, one rings may be drawn into and held in adjoin-
at each end of said series of die block rings, ing relation between said heads. 10
bolts 6 extending longitudinally of the In testimony whereof, I have signed my
5 shaft through said heads and through said name to this specification.
transverse openings in the web portions of
the die block rings, and securing means at

DAVID G. SIMPSON.
